(57) **CLAIM**

The ornamental design for a bag cover, as shown and described.

DESCRIPTION

FIG. 1 is a perspective view of a bag cover;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines showing a bag in FIG. 1 depict environment and form no part of the claimed design. All other broken lines on claimed surfaces depict features of the article and form no part of the claimed design.

1 Claim, 4 Drawing Sheets
